UNITED STATES PATENT OFFICE.

EMIL STERN, OF CHICAGO, ILLINOIS.

WRAPPING MACHINE.

Application filed April 5, 1926. Serial No. 99,746.

This invention relates to a wrapping machine and concerns itself particularly with the provision of a printing mechanism to be used in connection with wrapping machines, such as tire wrapping machines, for applying advertising or other printed indicia to the outer surface of the wrapping applied thereby.

Such indicia have heretofore sometimes been applied by securing previously printed or stamped gummed strips or labels to the exterior of the wrapping but such procedure is expensive and in certain cases undesirable.

It is an important object, therefore, of the present invention to provide a mechanism associated with a wrapping machine for directly printing or impressing desired indicia to the exterior of a wrapping applied to an article by said machine.

It is another object of this invention to provide a mechanism of the kind described which is particularly desirable for use with those types of tire wrapping machines which apply a spiral wrapping, the folds of which are adhesively joined together during the wrapping operation.

It is a further important object of this invention to provide a mechanism of the class described which is simple, durable and convenient to operate.

Other and further objects of this invention will be apparent from the disclosures in the specification and the accompanying drawings.

The invention (in a preferred form) is shown on the drawings and hereinafter more fully described.

On the drawings:

Figure 1 is a side elevation of a tire wrapping machine provided with the improved printing mechanism of this invention.

Figure 2 is a front elevation of the printing mechanism.

Figure 3 is a side elevation of the printing mechanism showing a fragmentary portion of the wrapped tire in section.

Figure 4 is a view looking from the rear of Figure 3 showing the printing mechanism raised to inoperative position.

Figure 5 is a fragmentary detail section on the line V—V of Figure 4 with parts omitted.

Figure 6 is an enlarged vertical section with parts shown in elevation taken through the ink container and a part of the inking mechanism.

Figure 7 is a fragmentary side elevation showing a modified form of printing mechanism.

Figure 8 is a fragmentary side elevation showing another form of printing mechanism embodying the principles of this invention.

Figure 9 is a fragmentary elevation with parts in section and part removed taken at right angles to the view shown in Figure 8 and with parts omitted.

Figure 10 is a front elevation of a readily detachable form of printing roller.

Figure 11 is an enlarged section on the line XI—XI of Figure 10.

Figure 12 is a side elevation of the printing roller shown in Figure 10.

Figure 13 is a fragmentary detail section on the line XIII—XIII of Figure 10.

As shown on the drawings:

The printing mechanism of this invention is adapted to be used in connection with a wrapping machine of the general type shown in Figure 1 where the reference numeral 1 indicates a base on which are mounted power driven tire supporting and driving rolls 2 which serve to support a tire casing 3 which is threaded through the eye of a shuttle 4 supported on said base 1 and adapted to be driven relative to the rotation of the tire and in a plane substantially perpendicular to the plane of said tire. The general type of wrapping machine to which I have shown the printing mechanism of my invention applied is fully described in a co-pending application of Paul Pierce, Serial No. 97,190, filed March 25th, 1926, with which I am familiar, although it will be understood that my invention may be readily applied to various types of wrapping machines.

Extending upwardly of the base 1 of the wrapping machine is a post 5 which serves to support an over-running follower or tire guiding mechanism 6 and which also adjustably supports my improved printing mechanism which will now be described.

Secured to the top of said post 5 is a suitable forwardly extending bracket 7 which carries a vertical track member 8, said track member in turn being slidably engaged by a suitable carriage 9. Supporting rods 10 extend outwardly in a horizontal direction from the face of the carriage 9 and mounted on the outer ends of said rods 10 is a supporting plate 11 which has supported there-

on a suitable ink container 12 (shown in detail in Figures 5 and 6) in which is journaled a metallic roller 13 which is adapted to carry ink to a suitable inking roller 14 5 rotatably mounted on a stub shaft projecting from the outer face of the plate 11. Also rotatably supported on a stub shaft 15 projecting from the outer face of said plate 11 is a printing roll 16 the outer face 10 of which is provided with desired indicia to be applied to the wrapping 3^a of the tire casing 3 when the same is wrapped. Secured to the inner side of the printing roll 16 is a gear 17 which meshes with an idler gear 18 pivoted on a stub shaft projecting from the face of the plate 11, said idler gear 18 in turn meshing with a gear 19 which is secured on the outside of the container 12 to the same rotatable shaft to which the metallic 20 roller 13 is secured. A filler cup 20 is provided through which ink or a similar printing medium may be introduced into the container 12 and a scraper plate 21, which is adjustable from the outside of the container 25 20 through a screw 22, is preferably provided for cleaning the surface of the roller 13 and removing excess ink therefrom. It will be noted that the container 12 is provided with a cover which has an opening 30 only large enough to permit a desired portion of the metallic roller 13 to project therethrough and, consequently, the danger of evaporation and drying out of the printing medium within said container 12 due to exposure of large areas to the air is minimized.

As will be noted from Figures 1 and 3, when the printing mechanism of this invention is in operative position, the printing roll 16 engages the wrapping 3^a at the periphery of the wrapped tire casing 3. The weight of the attendant mechanisms exerts sufficient pressure to print desired indicia on the said wrapping 3^a when the wrapped tire casing is rotated in the machine either 40 manually or through operation of the driving rolls 2, and it is thus possible to print desired indicia continuously around the periphery of said wrapping.

In order to provide for holding the printing mechanism away from the tire casing to permit of removal of the wrapped tire casing and of insertion of a new tire casing to be wrapped, I have provided a locking pin 23 which is slidably mounted in bosses 24 supported on an angle bar 25, a portion of which projects outwardly from the carriage 9 beyond the container 12. Said locking pin 23 is adapted to be normally urged toward the track 8 by a spring 26 surrounding the 50 same between the bosses 24 and when the printing mechanism is moved upwardly to inoperative position, said pin 23 engages a lateral extension 27 supported by the bracket 7 and thus holds said mechanism in its raised inoperative position. The lock-

ing pin 23 may be retracted to clear the extension 27 when it is desired to lower the device into operative position by a handle latch member 28 which is pivoted on the bar 25 and which is connected with the outer 70 end of said pin 23 by suitable link connection 29 in the form of a well-known lever release.

It will be appreciated that the printing rolls and attendant mechanisms may be 75 readily removed by sliding the same up past the top of the track 8 and a new mechanism substituted therefor when, for example, it is desired to change the color of the ink to be used.

In Figure 7, I have disclosed a modified form of printing apparatus embodying the present invention wherein the printing roller and inking apparatus which I have indicated in general by the reference numeral 16^a is 85 carried by a pair of supporting bars 30 which are pivotally supported on a bracket 31 extending outwardly from one end of the base 1 of the wrapping machine. The said bars 30 and the printing roller 16^a supported thereby are adapted to be brought into operative contact with the wrapping 3^a of a wrapped tire by means of a lever 31 which is attached to one of said supporting bars or to the pivot therefor and which is provided 90 with a usual hand released latch mechanism 32 which engages in a notched segment 33 to lock said lever 31 and the supporting bars 30 in a desired adjusted position.

Thus it will be evident by actuation of 100 said lever 31, it is possible to bring the printing roller into contact with the wrapping of a wrapped tire or to move said printing roller and attendant mechanisms out of the way when it is desired to remove the 105 wrapped and printed tire from the machine or to insert a new tire therein to be wrapped.

In Figures 8 and 9, I have shown a further modification wherein a printing roller 16^b and its attendant inking mechanism is 110 supported on resilient supports 34 extending upwardly from the base 1 of the machine between the supporting and driving rolls 2. In this construction, said printing roller 16^b is held in resilient contact with the periphery of the wrapped tire in order to print a desired indicia thereon when said wrapped tire is rotated in the machine. In order that 115 said printing roller 16^b and its attendant inking mechanisms may be moved out of the way when it is desired to move the wrapped tire from the machine or to insert a new tire to be wrapped therein, I have provided a transverse lever 35 which is pivoted on the base 1 of the machine and which is provided 120 with a usual hand-actuated latching mechanism for engagement with a notched segment 36 whereby said lever may be locked in its lower position. Said lever 35 is provided with a slot as indicated at 125 37 130

and engaged through said slot 37 is a pin 38 which projects outwardly from a portion of the inking mechanism on which the printing roller 16^b is mounted. Consequently, by virtue of this construction, the printing roller is held in resilient contact with the wrapping 3^a of a wrapped tire casing when it is desired to print indicia on said wrapping. On the other hand, when it is desired to render the printing mechanism inoperative and move the same out of the way for removal or insertion of tire casings, the lever 35 may be pushed downwardly until the latching mechanism thereof engages in a notch 36^a formed in the notched segment 36.

In Figures 10 to 13 inclusive, I have shown an improved means of detachably securing the printing roller which is designated on said figures by the reference number 16^c. In this construction, said printing roller is frictionally held on a rotatable hub 39 by a pair of readily releasable spring members 40 which are secured to said hub and which have outwardly projecting finger 25 grips 41 thereon. Said finger grips 41 afford shoulders 41^a which serve to prevent axial displacement of said printing roller. To insure driving engagement with a gear 17^a corresponding to the gear 17, said gear 30 is provided with a pin 42 extending outwardly from its face and slidably engaging in a sleeve 43 set in an aperture in said printing roller 16^c. This construction makes it possible for the operator to quickly and easily 35 change the printing roller when it is desired to print different indicia, for example, different tire sizes on the wrapping.

It will be apparent from the foregoing description that this invention provides a mechanism which is conveniently adapted to be mounted on existing types of wrapping machines for printing desired indicia on the exterior of wrappings applied thereby. Consequently, it provides an inexpensive 45 means of marking said wrappings in a desired manner without undue loss of time and in a manner which is convenient to the machine operator.

While the apparatus of this invention is particularly desirable for use in connection with wrapping machines which are adapted to apply a spiral wrapping, the folds of which are adhesively joined together, it will be readily appreciated that such apparatus 55 may be conveniently and effectively used with many types of wrapping machines.

I am aware that numerous details of construction may be varied through a wide range without departing from the principles 60 of this invention, and I therefore do not purpose limiting the patent granted hereon otherwise than necessitated by the prior art.

I claim as my invention:

1. In combination, a mechanism for advancing an article and applying a wrapping

thereto, and means adapted to be brought into contact with the article to print desired indicia on the wrapping as the article is advanced in said mechanism.

2. In combination, a mechanism for rotating an annular article and simultaneously applying a wrapping thereto, and means adapted to be brought into contact with the wrapped article to print desired indicia thereon as the article is rotated by said mechanism.

3. The combination with a tire wrapping machine, of means for printing desired indicia on the exterior of the wrapping applied by said machine, said means being actuated by the rotation of the tire in said machine.

4. The combination with a tire wrapping machine adapted to apply a spiral wrapping, the coils of which are adhesively joined together, of means associated with said machine for impressing a desired indicia on said wrapping.

5. The combination with a tire wrapping machine, of means adapted to rotatably engage a wrapped tire supported by said machine to impress desired indicia on the wrapping of said tire.

6. The combination with a tire wrapping machine, of a printing roller supported thereby and adapted to contact a tire wrapped thereby and movable relative thereto, and means for applying ink to said printing roller.

7. The combination with a tire wrapping machine, of a printing roller supported thereby and adapted to be brought into operative position in contact with a tire wrapped thereby and movable relative thereto, and means engaging a portion of said machine for holding said roller out of operative position.

8. The combination with a tire wrapping machine, of a printing roller supported thereby in position to engage the periphery of a wrapped tire, and means for applying a printing medium to said printing roller.

9. The combination with a tire wrapping machine, of means associated therewith and adapted to be held in contact with a tire wrapped thereby to print desired indicia on the wrapping of said tire.

10. The combination with a tire wrapping machine, of means associated therewith and adapted to be resiliently held in contact with a tire wrapped thereby to print desired indicia on the wrapping of said tire.

11. The combination with a tire wrapping machine, of a printing roller adapted to engage the wrapping of a tire wrapped thereby and to be rotated by the rotation of the tire in said machine.

12. The combination with a tire wrapping machine, of a printing roller adapted to engage the wrapping of a tire wrapped

- 4
- thereby and to be rotated by the rotation of the tire in said machine, and means for inking said printing roller driven by said printing roll.
- 5 13. In a wrapping machine for annular articles, means for supporting and rotating an article to be wrapped, and means for printing a desired indicia on the exterior of the wrapping applied to such articles,
- 10 said means being mounted in a plane passing between said supporting and rotating means.
14. In combination, a mechanism on which a wrapped annular article may be supported and rotated, means for printing a desired indicia on the wrapping of said article as the same is rotated, and readily releasable means for securing said printing means in operative position.
- 15 In testimony whereof I have hereunto subscribed my name.

EMIL STERN.
